MULTIPLE GENERATOR

Application filed September 24, 1929, Serial No. 394,879, and in Sweden October 8, 1928.

The present invention relates to a frequency converting electron valve relay for the generation of oscillations of desired frequency without disturbances by additional 5 undesired oscillations.

It has previously been proposed to use electron valves in push-pull connection as frequency converters, the anodes of said valves being then connected in parallel in 10 the common anode circuits, while the fundamental frequencies to be converted are supplied to the grids of the valves each with equal amplitude but opposite phase. It is further known to include a number of oscillatory circuits or impedances tuned to different frequencies in the said common anode circuit in order to be able to take out different frequencies. Said known arrangement is, however, affected with certain considerable 15 drawbacks. In the known arrangement it is possible to obtain a static characteristic curve of symmetrical parabolic form, but said symmetrical form is distorted under load, and as a consequence a number of undesired oscillations representing a considerable loss of 20 energy and causing disturbing effects are produced in the anode circuit in addition to the desired oscillations. Another considerable disadvantage of the known arrangement is that the lowest frequency is generated with the highest power, while the energy of the other oscillations is less, the higher the frequency of said oscillations. Further 25 the total output decreases very rapidly if it is attempted to increase the load of the relay.

The present invention has for its object to eliminate the said disadvantages. According to the invention the tuned oscillatory 30 circuits or impedances included in the anode circuit are connected with the grid circuit by means of a feed back connection so devised as to retransfer, independently of the frequency, a constant fraction of the anode potential, substantially eliminating the reaction of the anode voltage upon the control voltages of the relay, with equal phase to the two grids. Through the said compensation 35 of the reaction of the anode voltage on

the control voltages the characteristic of the two-valve relay retains its symmetrical parabolic form also in the dynamic state, i. e. when the relay is loaded. It is hereby rendered possible to take out the oscillations of different frequency generated in the anode circuit with outputs of the same order of magnitude. If, by way of example, the two fundamental frequencies ω_1 , ω_2 are supplied to the two grids, it is possible to take out from the anode 60 circuit the four transformed frequencies $2\omega_1$, $2\omega_2$, $\omega_1 - \omega_2$ and $\omega_1 + \omega_2$ with each about one quarter of the total power. It is further, through the constancy of the characteristic curve, rendered possible accurately to predetermine the valve senders, which is not possible with the known circuit arrangements. 65

The invention will be more closely described with reference to the accompanying drawings in which Figure 1 is a circuit diagram of a multiple generator according to an embodiment of the invention. Figure 2 is a circuit diagram of a modified embodiment. Figure 3 is a characteristic diagram. 70

In the two embodiments shown the relay 75 is composed of two three-electrode tubes 1, 1' the anodes 2, 2' of which are connected in parallel in relation to each other and connected to a common anode circuit composed of a number of oscillatory circuits. In the embodiment according to Figure 1 the grids 3, 3' of the two tubes are each connected to one terminal of the secondary coil 4 of a transformer, the primary winding 5 of which is supplied with the fundamental oscillation or oscillations to be converted. The middle point of the secondary winding is connected to the filament circuit over a grid biasing battery 6. 80

As the alternating potentials of the grids 3, 3' have mutually the same amplitude but directly opposite phases the characteristics of the two tubes may in Figure 3 be represented by two curves i_a and i'_a running symmetrically in relation to the axis of ordinates. In the diagram V_r and V'_r represent the mutually equal and directly opposite control voltages of the tubes 1, 1'. The relation between the anode currents i_a , i'_a of the two tubes and 95

the supplied control voltages may be analytically expressed through the formulas

$$i_a = C_o + C_1 V_r + C_2 V_r^2 + C_3 V_r^3 + \dots \quad (1)$$

$$i'_a = C'_o + C'_1 V'_r + C'_2 V_r^2 + C'_3 V_r^3 + \dots \quad (1)$$

As regards the control voltages V_r and V'_r the following relations exist:

$$V_r = V_a + \frac{V_a}{\mu} \text{ and } V'_r = -V_a + \frac{V_a}{\mu} \quad (2)$$

in which V_a designates the anode alternating potential, V_g the control alternating voltage, and μ the amplification ratio of the tubes.

If it is assumed that two different fundamental frequencies ω_1, ω_2 are supplied to the primary winding 5, which by way of example may be series connected with two generators of said number of frequencies, one has evidently

$$V_g = A_1 \sin \omega_1 t + A_2 \sin \omega_2 t$$

According to Equations (2)

$$\left. \begin{aligned} V_r &= A_1 \sin \omega_1 t + A_2 \sin \omega_2 t + \frac{V_a}{\mu} + \delta V_a \\ V'_r &= -A_1 \sin \omega_1 t - A_2 \sin \omega_2 t + \frac{V_a}{\mu} + \delta V_a \end{aligned} \right\} \quad (3)$$

in which formulas the last terms correspond to the compensating voltage transferred back to the grid circuit from the anode circuit. According to the present invention the grid voltage is so adjusted that

$$\delta V_a = -\frac{V_a}{\mu}$$

The resulting control voltages are then

$$V_r = A_1 \sin \omega_1 t + A_2 \sin \omega_2 t,$$

and

$$V'_r = -A_1 \sin \omega_1 t - A_2 \sin \omega_2 t = -V_r$$

The resulting anode current I_a is obtained by insertion into the Equations (1), thus:

$$I_a = i_a + i'_a = 2C_o + 2C_2 V_r^2 + 2C_4 V_r^4 + \dots \quad (4)$$

This resulting anode current is represented in the diagram, Figure 4, by the parabolic curve drawn in full lines. In most cases one may in the last equation neglect terms of higher order than the second for which reason the curve I_a may be practically considered as an exact parabola. One may now in the Formula (1) immediately neglect terms of the fourth degree and of higher orders and obtains thus for the resulting anode current

$$I_a = 2C_o + 2C_2 (A_1 \sin \omega_1 t + A_2 \sin \omega_2 t)^2 = 2C_o + C_2 A_1^2 (1 - \cos 2\omega_1 t) + C_2 A_2^2 (1 - \cos 2\omega_2 t) + 2C_2 A_1 A_2 [\cos(\omega_1 - \omega_2)t - \cos(\omega_1 + \omega_2)t]$$

The anode current contains thus the frequencies $2\omega_1, 2\omega_2, \omega_1 + \omega_2$, and $\omega_1 - \omega_2$. The anode-circuit includes a number of oscillatory circuits which are tuned each to one of said

frequencies. Said oscillatory circuits are in the shown embodiment mutually series connected and consist each of an inductance 7 and a capacity 8 connected in parallel. The inductance 7 are inductively connected each to one compensating coil 9, which compensating coils are series connected in relation to each other and to the grid biasing battery 6. By the retransfer by means of the coils 9 the two grids 3, 3' are supplied with mutually equal compensating potentials of the same phase sequence. Said compensating potential is in the Formulas (3) and (4) represented by the term δV_a . The factor δ in this term is so adjusted by a suitable selection of the degree of coupling between the coils 7 and 9 that the reaction of the anode potential upon the control voltage is exactly compensated as above described. The different anode circuit frequencies are tapped off from the appertaining tuned oscillatory circuits over the terminals 10.

If the two fundamental frequencies ω_1, ω_2 are obtained from mutually independent generators it may occur that a higher harmonic of the one fundamental oscillation in the grid circuit so interferes with the other fundamental oscillation that an interfering tone of low frequency is produced in the anode circuit. If, by way of example, the one fundamental frequency ω_1 is intended to have twice the value of the other one, the first of the higher harmonics of the latter fundamental frequency may on account of involuntary variations in the relation between the fundamental frequencies interfere with ω_1 and thus cause a disturbing tone. The two frequencies $\omega_1 + \omega_2$ and $\omega_1 - \omega_2$ occurring in the anode circuit are also dependent on the variations in the frequencies ω_1 and ω_2 supplied to the grids.

This inconvenience will be entirely eliminated by the embodiment shown in Figure 2. This embodiment differs from the above described only therein that the secondary winding of the input transformer is divided into two halves 11, 11' and that a back coupling coil 12 and 12' respectively is included in series with each half. Said two back coupling coils are inductively coupled to one of the oscillatory circuits included in the anode circuit. The back coupling coils 12, 12' are over the grid biasing battery 6 both connected to the filament circuit.

In this embodiment only a single fundamental oscillation with the frequency ω is supplied from the outside which frequency is thus supplied to the primary terminals of the input transformer. The other fundamental frequency is, on the other hand, obtained by means of the back coupling of one of the multiple frequencies occurring in the anode circuit through the intermedium of the coils 12, 12'. In the circuit arrangement shown in Figure 2 the second harmonic 2ω generated in the anode

circuit is in this way transferred back to the grid circuit and is there superimposed upon the fundamental oscillation supplied from the outside. The oscillatory circuit for 2ω is thus in this case connected to the grid circuit through a double back coupling, i. e. by means of a compensating coil 9 through which the two grids 3, 3' obtain compensating potentials of mutually equal phase sequence and of the frequency 2ω and also by means of the two back coupling coils 12, 12' which transfer the frequency 2ω to the two grids with mutually equal amplitudes but with opposite phases.

In the example shown in Figure 2, thus:

$$\omega_1 = 2\omega$$

$$\omega_2 = \omega$$

In the anode circuit the frequencies $2\omega_1 = 4\omega$, $2\omega_2 = 2\omega$, $\omega_1 + \omega_2 = 3\omega$ and $\omega_1 - \omega_2 = \omega$ are then obtained.

If desired, one may of course retransfer more than one of the combination tones occurring in the anode circuit. If, by way of example, the grid circuit is supplied with the two oscillations ω and 4ω generated in a separate generator and the two oscillations 3ω and 5ω are retransferred from the anode circuit, oscillations of the frequencies 3ω , 5ω , 7ω and 10ω may be obtained in the anode circuit. For this purpose the retransfer coils 12, 12' are connected to the two oscillatory circuits which are tuned to the frequencies 3ω and 5ω .

The circuit arrangement according to Figure 2 offers the advantage in comparison with the first described arrangement that in case of fluctuations in the fundamental frequency supplied from the outside all frequencies generated in the anode circuit will vary in exactly the same mutual proportion. Higher harmonics of the fundamental frequency, which may occur, will thus under all conditions either completely coincide with or considerably differ from the frequencies retransferred from the anode circuit to the grid circuit and will thus not cause disturbing tones.

If it is desired to obtain oscillations of a still higher frequency one of the frequencies generated in the anode circuit may be tapped off therefrom and used as fundamental frequency in another static converter according to Figure 2 etc. Two of the frequencies in the anode circuit may also be tapped off and together supplied to a converter according to Figure 1. In this manner a plurality of converters may be connected in cascade, arbitrary multiples of a given fundamental frequency being then obtainable. If the frequencies 3ω and 4ω , by way of example, are tapped off from the anode circuit in Figure 2 and supplied to the input side of a succeeding converter according to Figure 1 the frequencies 6ω , 8ω , 7ω and ω are obtained in the anode circuit of the latter. If again only the frequency 4ω is tapped off and introduced on the

input side of a succeeding converter according to Figure 2 the frequencies 8ω , 4ω , 12ω and 16ω etc. are obtainable.

In many cases it is preferred to include one or several filter-sections or the like in the anode circuit of a multiple generator instead of oscillatory circuits as shown in Figures 1 and 2.

The static converter according to the invention shows the following advantages:

1. Only frequencies built up by adding and subtracting the fundamental frequencies in the grid circuits are included in the anode circuit.

2. Any desired frequency may be obtained in the anode circuit by a suitable selection of said fundamental frequencies.

3. Just the desired frequency may be tapped off from the anode circuit independently of other frequencies.

4. Any desired frequency may be generated by the connection of several converters in cascade.

5. The generated frequencies may be obtained practically free from higher harmonics.

6. The obtainable power output is nearly the same in the different oscillatory circuits included in the anode circuit in contradistinction to hitherto known valve generators in which the power output very rapidly decreases with a rising frequency of the higher harmonics.

7. A multiple generator according to the invention may be exactly dimensioned on the basis of an exact theoretical precalculation.

The features according to 3 and 6 are essentially due to the fact that the multiple generator according to the invention does not operate as an oscillator in the ordinary meaning of the word, i. e. it does not operate with back-coupling of the kind usually applied in an ordinary valve generator. In contradistinction thereto also the inner back coupling in the valves in the present arrangement is compensated by means of the compensating coils 10.

On account of said characteristic features the circuit arrangement according to the invention is especially suitable to be applied, by way of example, in telephone systems in which high frequency oscillations are used as carrier waves to transmit speech waves along telephone lines. An entire line system may then be fed with oscillations which are obtained from a single common fundamental frequency by means of static conversion. Said fundamental frequency may be of a comparatively low frequency, lying, by way of example, within the range of voice frequencies and may then be converted to higher frequencies by connecting two or several frequency converting multiple generators in cascade according to the invention. A fundamental oscillation with a completely constant

frequency may, by way of example, be obtained by means of a generator of the tuned fork type. The different high frequent oscillations on the lines are thereby also obtained with a completely constant frequency.

5 The compensation of the reaction of the anode load upon the control voltages of the valve may also take place in other manner than by the connection of the anode circuit 10 to the grid circuit as above described. By way of example, said compensation may be brought about by the use of special electron valves, such as shielded grid valves or pentode valves or the like, in which a shielding 15 grid is disposed between the control grids and the anodes and said shielding grid is maintained at a constant potential.

We claim

20 1. A frequency converting electron valve relay comprising two grids, means for supplying fundamental oscillations with opposite phase to said grids, two anodes connected in parallel in a common anode circuit, a number of impedances tuned to different frequencies and included in said anode circuit, and feed back connection adapted to retransfer, independently of the frequency, a constant fraction of the anode potential, substantially eliminating the re-action of the anode voltage 25 upon the control voltages, with equal phase to the two grids.

20 2. A frequency converting relay as claimed in claim 1, characterized by that the grid biasing voltage is negative and substantially 30 equal to the $\frac{1}{\mu}$ part of the constant anode potential.

35 3. A frequency converting electron valve relay comprising two grids, means for supplying fundamental oscillations with opposite phase to said grids, two anodes connected in parallel in a common anode circuit, a number of impedances tuned to different frequencies and included in said anode circuit, and 40 a number of feed back coils each connecting one of said tuned impedances inductively with the grid circuit so as to retransfer a potential of the corresponding frequency, substantially 45 eliminating the re-action of the anode voltage upon the control voltages, with equal phase to 50 the two grids.

4. A frequency converting relay as claimed 55 in claim 3, characterized in that the compensating coils are connected into circuit between the filament circuit and the middle point of an impedance which is connected up between the two grids and upon which the fundamental frequencies are impressed.

60 In testimony whereof we affix our signatures.
